UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed January 10, 1924. Serial No. 685,339.

This invention relates to typewriting machines of the fan-fold or continuous billing type, one form of which is shown in the patent to Wernery & Smith, No. 1,132,055, dated March 16, 1915, and more particularly to machines for typing selectively on any one of a plurality of packs of web-plies and interleaved carbons positioned in the machine in readiness to be fed around the platen when desired.

In machines of the above-mentioned type, superposed plies or webs of suitable material, together with interleaved carbon-sheets, are fed around the platen during typing, and, after the typing on one section has been completed, the superposed plies or webs are straightened and a relative shifting between such web-plies and carbon-sheets effected preparatory to using the carbon-sheets with the next unused section to be typed. Usually each section typed is severed as soon as the proper association of the carbon-sheets with the next unused section of the web-plies is completed. The web-plies may be entirely separate, or may be joined at their edges, as, for example, in fan-folded webs, and preferably each ply has thereon a succession of like forms, the forms of the superposed web-plies being in register. For certain classes of work, it has been found desirable to have a plurality of packs of such web-plies together with interleaved carbons so arranged in the machine that substantially all that is necessary preparatory to typing on any selected pack is to insert the leading end of such pack around the bottom of the platen to the printing line. It has been proposed to arrange such packs in superposed relation. Under such conditions, the packs extend to the platen-frame from guiding devices at different heights, and it is impossible to straighten certain packs beneath the platen to as great an extent as others.

An object of the present invention is to provide controlling means for the packs of web-plies and interleaved carbon-sheets such that, when any pack is in position for use, its path from the associated guiding device to the platen is substantially the same as for any other of such packs which may be put into use.

According to the present embodiment of the invention, the separate packs of web-

plies may be arranged side by side, and the carbon-sheets interleaved between said web-plies may be controlled by carbon-carriers supported on a common frame or table which may be detachably connected at its forward end with the rear of a typewriter-carriage, to permit any one of said packs to be brought into co-operative relation with the platen, by effecting a lateral shifting of said table relatively to said carriage.

Provision may be made of means to secure said table to the carriage when any adjustment of the table relatively to the carriage has been effected.

Other features and advantages will hereinafter appear.

In the accompanying drawings,

Figure 1 is a top plan view, showing the invention applied to an Underwood typewriter of the fan-fold type.

Figure 2 is a side elevation, taken in section along the line 2-2 of Figure 1, looking in the direction of the arrows.

Figure 3 is a sectional front elevation, taken along the line 3-3 of Figure 2, looking in the direction of the arrows.

Figure 4 is a view similar to Figure 3, but showing the carbon-carrier table shifted laterally with reference to the typewriter-carriage, to bring a different carbon-carrier into position for use.

Figure 5 is a view similar to Figure 2 of a modified form of the invention.

Figure 6 is a front elevation, taken along the line 6-6 of Figure 5, looking in the direction of the arrows.

Upon the depression of keys, not shown, type-bars 10 are swung upwardly and rearwardly to cause types 11 thereon to strike against a platen 12 mounted by means of an axle 13 in arms 14 of a platen-displacing frame 15, said arms being pivoted at their forward ends on a shaft 16 extending between the ends 17 of a platen-frame 18, and normally resting at the rear on a shaft 19 journaled in the ends 17 of the platen-frame. Mounted on the shaft 19 are hooks 20 to engage pins 21 projecting laterally from the arms 14 of the platen-displacing frame, and to thereby hold the platen-displacing frame 15 in its normal position, and preferably one of the hooks 20 is provided with a finger-piece 22 for shifting the hooks 20 to ineffective position, to permit the platen to be dis-

placed, when necessary, in the operation of the fan-fold machine. The platen-displacing frame 15 also comprises a paper-table 25 supported on the arms 14 of said platen-displacing frame, and having attached thereto a gage-bar 24 on which a gage 25 may be adjustably secured at any desired position by means of a set screw 26. The platen-frame 18 forms part of a carriage 27 mounted at its rear on a transverse rail 28 fixed to the main frame 29 of the machine.

Projecting rearward from a transverse bar 30 of the typewriter-carriage 27, are brackets 31 which serve to support the forward end 15 of a rearward extension 32 of the carriage which travels therewith in letter-feeding direction. The rearward extension of the carriage comprises front and rear members or rods 33 and forwardly and rearwardly 20 extending members or rods 34, said rearward extension being guided on a rear rail 35 on a supplementary main frame 36 by means of rolls 37 engaging said rail, at the top and bottom thereof, and pivotally mounted on 25 brackets 38 attached to certain of the forwardly and rearwardly extending rods 34.

As herein disclosed, provision is made of three carbon-carriers 39 arranged transversely of the machine to run forwardly and 30 rearwardly on rails 40 mounted on forwardly and rearwardly extending members 41 in a frame 42, which comprises additional forwardly and rearwardly extending members 41 intermediate those carrying the rails 40 and transverse members 43 at the front and rear. At each end the rearward transverse member 43 is provided with downwardly-extending brackets 44 connected by a member or rod 45 slidable in perforations 40 in brackets 46 extending upwardly from the ends of the rear member 33. The front member 43 of the frame is also provided with forwardly-extending brackets 47 carrying a transverse rod 47^a to enter slots 48 in ears 49 extending upwardly from the brackets 31, to connect the frame 42 with the typewriter-carriage 27.

In order to locate the frame 42 so as to bring the track of a selected carbon-carrier to the proper position with relation to the platen 12, the transverse rod 47^a is provided with notches 50, the diameter of which is greater than the width of the slots 48, to receive the portions of the ears 49 at the rear side of the vertical slots 48. These notches 50 serve to position the carbon-carrier tracks definitely with reference to the carriage 27. Pivoted on the ears 49 are hooks or latches 51 to engage the top of said rod 47^a to hold it in said slots 48 when placed therein, each of said latches being urged to forward position by a leaf-spring 52, and being provided with a pin or stop 53 to engage the corresponding ear 49 and limit the rearward movement of 60 the latch, and with a finger-piece 54 at the

upper end for use in releasing the latch. It will be seen that, upon releasing the latches 51 to permit lifting the rod 47^a out of the slots 48, the frame 42 may be swung upwardly about the axis of the rod 45 and 70 shifted laterally by sliding the rod 45 in the brackets 46 to bring the track of another carbon-carrier 39 into proper position with reference to the platen, to replace the carbon-carrier previously in operative position. 75 The frame 42 may then be swung downwardly to cause the fingers at the rear of the slots 48 to enter the corresponding notches 50 in the rear side of the rod 47^a and to permit the latches 51 to move into effective 80 position over said rod, and to seat themselves in notches 55 in the front of the rod 47^a. It will be seen that the notches 55 serve to determine the various positions of the frame 42 in the same manner as the pairs 85 of notches 50.

Each of the carbon-carriers 39 comprises a base 56 provided with grooved rolls 57 to engage the edges of the corresponding rails 40, and at opposite sides of each base stepped blocks 58 are provided to support carbon blades or holders 59 to which are attached the rear ends of carbon-sheets 60 interleaved between the plies 61 of packs 62 of web-plies fed from suitable sources of supply over a rear guide 63 supported in upward extensions of the brackets 44. To maintain such packs in suitable position with reference to the carbon-carriers 39, provision may be made of side gages 64 adjustable along the guide 63. 95 When not in use, the packs 62 with their interleaved carbons are folded back over the corresponding carbon holders or blades 59, as indicated in Figure 2.

When any one of the packs 62 of web-plies is to be used, the platen-displacing frame 15 is released by means of the finger-piece 22 and the platen-displacing frame is swung upwardly and forwardly. The leading end of the selected pack of web-plies together with the interleaved carbons is then drawn forwardly between suitably positioned side gages 65 on a transverse rod 66, supported at its ends in the brackets 47, and is passed beneath the platen, and, at the 115 delivery side of the platen, between the platen and a knife 67 associated with the platen-displacing frame 15. The platen 12 is then restored to its normal position and typing effected in the usual manner. When 120 the typing upon one set of forms has been completed, the platen is again displaced, the leading edges of the web-plies advanced to the leading-edge gage, and the carbon-sheets retracted by means of a handle 68 attached 125 to the carbon-carrier 39 in use. The platen may then be restored to normal position, the typed sections severed by the knife 67, and the operation repeated. It should be understood that the pack to be used is neces- 130

sarily the one associated with the carbon-carrier whose track is operatively positioned with reference to the platen.

When it is desired to type on one of the other packs of web-plies, the leading end of the pack formerly in use is withdrawn from the platen and folded rearwardly over the carbon blades or holders of the corresponding carbon-carrier, as indicated in Figure 2. The latches 51 are then drawn forwardly by the finger-pieces 54 and the rod 47^a lifted out of the slots 48 to free the frame 42 from the carriage, and the frame 42 is slid transversely of the machine to a position to bring the selected carbon-carrier 39 and its track to the proper position with reference to the carriage 27. The rod 47^a is then swung into the slots 48, the exact position of the frame being determined by the slots 50, which must coincide in position with the ears, the latches 51 being cammed forwardly by the rod 47^a in its downward movement and then released to snap back into effective position to enter slots 55 and by engagement with the upper side of said rod 47^a to hold it in the slots 48. The leading end of the selected pack may then be drawn forward and passed under the platen as described for the first pack selected.

In the form of the invention shown in Figures 1 to 4, inclusive, the frame or extension 32 is fixed to the carriage and consequently moves to the same extent, so that the rear rail 35, supported on the auxiliary frame, may be of moderate length. The frame 42, however, is shifted with reference to the extension 32 and when, for example, the frame 42 is in one of its extreme positions, the left, as shown in Figure 4, considerable twisting stress is exerted on the extension 32, and the lifting of the right side of the extension 32 from the rail 35 is prevented by the lower roll 37 on the right-hand bracket, as seen in Figure 4. The use of rolls 45 to engage the lower side of the rail permits easy movement of the extension with the carriage notwithstanding the twisting stress exerted. In the form of the invention shown in Figures 5 and 6, the frame or extension 32 is omitted and the carbon-carriers are mounted directly on a frame 69 similar to the frame 42 of the form illustrated in Figures 1 to 4 but supported directly on a rear rail 70 by means of grooved rolls 71 resting 50 on the rail 70 and pivoted in brackets 72 attached to certain forwardly and rearwardly extending members 73 of the frame 69, which also comprises front and rear transverse members 74. To prevent the rolls 60 from leaving the rail, the lower ends of the brackets may be offset to engage the lower side of the rail. Certain of the forwardly and rearwardly extending members have flat rails 75 thereon to engage in grooved rolls 65 71 pivoted in the bases 56 of the carbon-

carriers 39, which may be the same as those disclosed in Figures 1 to 4, inclusive. The frame 69 is also provided at its rear with a guide or rod 76 supported in upright brackets 76^a and provided with side-edge gages 76^b for the packs of web-plies as they pass from the sources of supply to the carbon-carriers 39. At the front the frame may be detachably connected with the carriage in the same manner as the frame 42 disclosed in Figures 1 to 4, and provision may also be made of a guide 66 corresponding to the guide 66 shown in Figure 2 and provided with adjustable side gages 65 as in Figure 2.

In the form of the machine disclosed in Figures 5 and 6, the extension or frame 69 may be moved not only the amount due to the travel of the carriage, but to an additional amount due to the shifting of the extension relatively to the carriage 27 to position the carbon-carriers 39 at the sides in alignment with the carriage. The rail 70 is therefore of greater length than the rail 35 shown in Figures 1 to 4, inclusive, and, in order to render the rail 70 sufficiently rigid, provision may be made of supporting brackets 72 extending laterally from the sides of the auxiliary frame 36.

Preferably each pack 62, when in use, is guided around the bottom of the platen and between the platen and the releasable front and rear feed-rolls 77 and 78, respectively, by a rear paper-table 79 and a paper-apron 80. Obviously, when the platen is displaced, the pack will be released. To rotate the platen for feeding the pack gripped between the platen 12 and the feed-rolls 77 and 78, provision may be made of gears 81 on the ends of the platen-axle 13 and, when the platen 100 is in normal position, in alignment with gears 82 on the inner ends of stub-shafts 83 journaled in the ends 17 of the carriage and having at their outer ends finger-wheels 84. The gears 81 and 82 at each end of the platen 105 mesh with a broad pinion 85 mounted on the shaft 16, so that the platen is operatively connected at all times with the finger-wheels 84. If desired, provision may be made of line-space mechanism (not shown) to act on 110 one of the stub-shafts.

Variations may be resorted to within the scope of the invention, and portions of the improvements may be used without others.

Having thus described my invention, I claim:

1. In a typewriting machine, in combination, a platen, a letter-feeding carriage therefor, a plurality of carbon-carriers to hold carbon-sheets in interleaved relation with web-plies of a plurality of packs, tracks, one for each carbon-carrier, and means for adjusting said tracks relatively to said carriage so that one pack at a time will be in position for use with the platen. 125

2. In a typewriting machine, in combination, a platen, a letter-feeding carriage therefor, a plurality of carbon-carriers to hold carbon-sheets in interleaved relation with web-plies of a plurality of packs, parallel tracks, one for each carbon-carrier, and a track support to travel with the carriage and shiftable relatively thereto to locate with reference to the platen any one of said tracks and the corresponding carbon-carrier in effective position for typing on the corresponding pack. 70
3. In a typewriting machine, the combination of a carriage, a platen on said carriage, a rearward extension to travel with said carriage, a plurality of carbon-carriers arranged side by side and carried by said extension for movement fore and aft of the machine individually to and away from the platen with work-webs and interleaved carbon-sheets, and means to shift the carbon carriers collectively to render them selectively co-operative with the platen one at a time with their associated work-webs, said means including a frame to support the carbon-carriers, said frame being supported on said extension, and means to enable a sidewise adjustment of the frame on said extension. 75
4. In a typewriting machine, in combination, a platen, a letter-feeding carriage therefor, a plurality of carbon-carriers to hold carbon-sheets in interleaved relation with web-plies of a plurality of packs, tracks, one for each carbon-carrier, a device to support said tracks in the same horizontal plane and shiftable relatively to the platen to bring any one of said tracks into effective position with reference to the platen, and means to secure said device to the carriage to travel therewith. 80
5. In a typewriting machine, in combination, a platen, a letter-feeding carriage therefor having a rearward extension, a plurality of carbon-carriers to hold carbon-sheets in interleaved relation with web-plies of different packs, a plurality of carbon-carrier tracks in substantially the same horizontal plane, a frame to carry said tracks and slidable on said extension transversely of the machine, and means to latch said frame to said carriage when any one of said tracks is in effective position. 85
6. In a typewriting machine, in combination, a platen, a letter-feeding carriage therefor having a rearward extension, a plurality of carbon-carriers to hold carbon-sheets in interleaved relation with web-plies of different packs, a plurality of carbon-carrier tracks in substantially the same horizontal plane, a frame to carry said tracks and slidable on said extension lengthwise of the platen, and means for locating said frame in mechanically-determined positions with the selected carbon-carrier and associated pack in position for use. 90
7. In a typewriting machine, in combination, a platen, a letter-feeding carriage therefor having a rearward extension, a plurality of carbon-carriers to hold carbon-sheets in interleaved relation with web-plies of different packs, a plurality of carbon-carrier tracks in substantially the same horizontal plane, and a track-carrying frame slidable transversely on said extension and swingable to disconnect its forward end from the carriage to permit such sliding and swingable in the opposite direction to connect the track-carrying frame in adjusted position. 95
8. In a typewriting machine having a platen, the combination with a letter-feeding carriage, of separate devices for holding separate sets of carbon-sheets in interleaved relation with separate packs of work-sheets or webs, a support for said separate devices, a fixed guide upon which said support is mounted to be shifted lengthwise thereof and independently of the carriage to enable any one of said devices to be brought into co-operative relation with said platen, and means for maintaining such co-operative relation when established. 100
9. In a typewriting machine, the combination of a carriage, a platen on said carriage, a rearward extension to travel with said carriage, a plurality of carbon-carriers arranged side by side and carried by said extension, said carbon-carriers being movable fore and aft of the machine individually to and away from the platen with work-webs and interleaved carbon-sheets, and means to facilitate sidewise adjustment of said carbon-carriers to various positions on said extension to render the carbon-carriers, one at a time with their associated work-webs, selectively co-operative with the platen, said means including a frame supporting the carbon-carriers, said frame being pivoted at one end to said extension, and means at the other end of said extension to enable said frame to be released so that said frame may be moved sidewise with the carbon-carriers and webs on said extension. 105
10. In a typewriting machine, the combination of a carriage, a platen on said carriage, typing mechanism, devices on said carriage for holding carbon-sheets in interleaved relation with separate packs of work-sheets or webs, and means for effecting a movement of said holding devices on said carriage relatively to said typing mechanism to establish an operative relation between the typing mechanism and any desired pack. 110
11. In a typewriting machine having a platen, the combination with a letter-feeding carriage, of separate devices for holding separate sets of carbon-sheets in interleaved relation with separate packs of work-sheets or webs, means to selectively render effective any of the packs of work-sheets, said means 115

including a supporting device for said separate holding devices shiftable to move any one of said devices with its carbons and pack into co-operative relation with said platen and

5 the remaining devices with their carbons and packs out of co-operative relation with the platen, and means for maintaining such co-operative relation when established.

12. In a typewriting machine, the combination of a carriage, a rearward extension rigidly secured to said carriage to travel therewith, a plurality of carbon-carriers carried by said extension, said carbon-carriers being arranged side by side and movable

10 fore and aft of the machine individually to and away from the platen with work-webs and interleaved carbon-sheets, and means to render said carbon-carriers, one at a time with their associated work-webs, selectively

15 effective with the platen, said means including a frame supporting the carbon-carriers, said frame being pivoted at the rear on said extension, supports at the forward end of said extension upon which the frame rests,

20 the forward end of the frame having slots, a locating device on said extension to engage in said slots to establish the relation between said frame and said extension and prevent accidental shifting between them,

25 and a latch to hold the frame down against said supports, said latch being operable to release the forward end of the frame so that said frame may be swung free of the locating device to enable said frame 30 to be moved sidewise on said extension with said carbon-carriers to other positions.

13. In a typewriting machine having a platen, the combination with a letter-feeding carriage, of separate means, arranged side by side, connected to travel with the carriage 40 for holding separate sets of carbon-sheets in interleaved relation with separate packs of work-sheets or webs, and means to facilitate the feeding of said packs, one at a time, to 45 the same field of the platen, and maintaining the remainder out of use.

14. In a typewriting machine, in combination, a platen, a letter-feeding carriage therefor, a rearward extension of said carriage to travel therewith, separate devices 50 for holding separate sets of carbon-sheets in interleaved relation with separate packs of work-sheets or webs, and a support on which said holding devices are mounted side by side, and slideable on said extension transversely of the machine to bring any one of said holding devices into operative relation with the platen.

15. In a typewriting machine, in combination, a platen, a letter-feeding carriage therefor, a rearward extension of said carriage to travel therewith, a plurality of carbon-carriers for holding separate sets of carbon-sheets in interleaved relation with 60 separate packs of work-sheets or webs and

for retracting the carbon-sheets from typed sections of the webs to unused sections on which typing is to be effected, a plurality of sets of tracks to guide the carbon-carriers individually away from the platen during a 70 carbon-retraction operation, and a support on which said tracks for the carbon-carriers are mounted side by side, and slideable collectively on said extension transversely of the machine to bring any one of said tracks 75 with its carbon-carrier into operative relation with the platen while the remaining carbon-carriers are brought to ineffective positions.

16. In a typewriting machine, the combination of a letter-feeding carriage, a platen thereon, an extension to travel with said carriage, devices on said extension to conduct a plurality of work-packs over said extension, and means to enable said extension 80 to be shifted relatively to said carriage to bring any one of the work-packs into co-operative relation with the platen.

17. The combination with typewriting mechanism, comprising a carriage, of means to travel with the carriage to conduct separate work-sheets disposed side by side to the typing mechanism, said carriage having a range of travel equal substantially to the width of one of the work-sheets, and means to enable an adjustment of the conducting means to bring any one of the work-sheets within the range of travel of the carriage to co-operate with the typing mechanism. 90

18. In a typewriting machine, the combination of a carriage, a platen on said carriage, an extension on said carriage to travel therewith, means carried by said extension to conduct a plurality of work-webs fore and aft of the machine, and means to facilitate a sidewise adjustment of the work-webs collectively to render any one of them co-operative with the platen, said means including a frame over which the work-webs are conducted and which frame is supported by said extension, a set of guides on said frame, one set for each work-web, and means to enable the frame to be adjusted sidewise on said extension. 100

19. In a typewriting machine, the combination of a carriage, a platen on said carriage, an extension to travel with said carriage, and means supporting a plurality of work-sheets arranged side by side, said supporting means being shiftable laterally on said extension to bring any one of said sheets into operative relation with the platen. 115

20. In a typewriting machine, the combination of a carriage, a platen on said carriage, an extension to travel with said carriage, means supporting a plurality of work-sheets arranged side by side, said supporting means being shiftable laterally on said extension to bring any one of said 125 sheets into operative relation with the platen. 130

sheets into operative relation with said platen, the supporting means being pivoted at one end to said extension, and holding means at the other end of the supporting means to hold the latter in its adjusted position, said supporting means being releasable from the holding means, so that it may be swung about its pivot to disconnect it preparatory to sliding it laterally to a different position on said extension.

21. In a typewriting machine, the combination of a carriage, a platen on said carriage, a rearward extension over which a plurality of sets of work-webs, each having a set of interleaved carbon-sheets, may be conducted to the platen, carbon-carriers, one for each set of sheets, to which the carbon-sheets are attached, tracks to guide the carbon-carriers to and away from the platen, a swing-frame carrying the platen, said swing-frame being pivoted on said carriage to swing the platen to an abnormal position, so that the effective work-web may be straightened out to enable the carbon-sheets

to be shifted to a fresh portion of the work-web, means whereby the carbon-carriers are supported in a horizontal plane, so that each work-web may be substantially horizontal when in use during a carbon-shifting operation, said means including a horizontally disposed frame mounted on said extension and supporting said tracks, and means to enable said frame to be shifted sidewise on said extension to bring any one of said webs and its interleaved carbon-sheets into co-operative relation with the platen.

22. In a typewriting machine, the combination of a carriage, a platen on said carriage, and means to conduct a plurality of individual work-webs arranged side by side to the platen, said means comprising a device to travel with said carriage, and means to facilitate adjustment of said device in the direction of travel of said carriage to render any one of the webs selectively effective with the platen.

JOHN WALDHEIM.
